THEODORE SWANSON, OF LYNN CENTER, ILLINOIS.

WORK-BENCH.

1,112,729.

Specification of Letters Patent.

Patented Oct. 6, 1914.

Application filed May 9, 1914. Serial No. 837,567.

To all whom it may concern:

Be it known that I, THEODORE SWANSON, residing at Lynn Center, in the county of Henry and State of Illinois, have invented 5 a new and Improved Work-Bench, of which the following is a specification.

This invention, which relates to work benches, is more especially designed to serve 10 as a carpenter's bench, and it comprehends generally a bench of the general type stated having an improved means whereby lumber 15 may be conveniently held for being planed off evenly and square, with perfect accuracy and ease and without the necessity of testing the work with squares, gages or other like implements.

Primarily, my invention has for its object 20 to provide an improved work bench of the kind stated of a simple, compact and economical construction, in which the parts are 25 coöperatively so combined and arranged that they can be so formed to the desired sizes and shapes that they can be readily assembled for use, and which are so joined that the bench may be worked from either the right or left hand side.

My invention also seeks to provide, in a 30 bench of the character stated, a simple and easily adjusted and manipulated guiding means for the planer, whereby in use it will plane a perfectly straight edge to square 35 perfectly with the flat side of the board being planed and in which the parts are so connected and operatively combined that the entire bench may be easily moved about without the necessity of taking out a part.

Again, my invention has for its purpose 40 to provide a work bench of the character mentioned whose parts are so formed and adapted for being operatively so connected that the said parts may be, when desired, readily taken apart in sections or in separate pieces.

With other objects in view that will hereinafter appear, my invention consists of 45 certain improvements in work benches that embody the peculiar construction and novel combination of parts, all of which will be hereinafter fully explained, specifically pointed out in the appended claims and illustrated in the accompanying drawings, in which:

Figure 1 is a perspective view of my invention, the hinged top or flat planing board

being shown in the operative position, a part thereof being broken away. Fig. 2 is 55 a longitudinal section of my improved work bench the hinged top board being at its swung down position. Fig. 3 is a cross section thereof taken on the line 3—3 on Fig. 1. Fig. 4 is a cross section taken on 60 the line 4—4 on Fig. 2.

In carrying out my invention, I form the framing of the bench in the manner best shown in Figs. 1 and 2 of the drawing, by reference to which it will be seen that the 65 oppositely disposed horizontal timbers 1—1, which form the guideway for the planing implement hereinafter referred to, are bolted to the inner sides of the upper ends of a series of sets of oppositely disposed uprights or posts 2—2, three of such sets of posts being shown, one set at each end of the bench and one set centrally thereof. The lower ends of the uprights 2—2 are fastened 70 to the inner edges of a pair of longitudinally 75 extended base timbers or boards 3—3 in turn mounted upon and secured to the bottom cross members 4—4. For holding the opposite end sets of the uprights 2—2 rigidly, they are braced by the metal cross 80 bars 6 and 7 that join with the posts 2 and the timbers 3 and 4, as shown. The upper edges of the guide timber 1—1, in practice, extend, above the posts, the upper edges being in a plane slightly below the upper 85 edges of a pair of longitudinal boards 80—80 secured upon the outside of the posts or uprights 2—2 and which extend the full length of the bench.

8—8 designate hanger bars pendent from 90 one of the guide timbers 1 to which they are bolted and 9 is a bottom bar bolted to the lower ends of the hangers 8, and which extends the full length of the bench.

10 designates a longitudinally extended 95 bar, located between the opposite sets of uprights or posts 2, and which form a supporting member for the board whose edges are to be planed and the said bar is adjustably supported for vertical movement with respect to the planer guides 1 in the manner best shown in Figs. 1 and 3, from which it will be noticed the bar 10 at each end, has a laterally projected bracket 11 formed with a vertical threaded aperture 12 for receiving 100 105 the vertically positioned adjusting screw

shafts 13 whose lower ends have stepped bearings in brackets 14 that are secured to and projected laterally from the bottom bar 9.

5 By reason of arranging the several parts, so far as described, it is apparent that the board whose edges are to be planed is edge-wise supported upon the bar 10, and since the said bar is vertically adjustable, the upper edge of the board to be planed can be readily brought into the desired position relatively to the guide members 1-1.

10 The upper ends of the screw shafts are journaled in brackets 15 that project inwardly from one of the side boards 80, it being understood that the screw rods are so mounted that by turning them, in opposite directions, the board supporting bar 10 can be raised or lowered, as desired.

15 20 The rods 13 may be provided with turning handles 16, at the lower end, as shown in Fig. 3, but for more conveniently actuating them they are preferably provided with bevel pinions 17 for engaging with like pinions 18 on the crank shafts 19-19.

25 It should be stated that the supporting bar 10 is narrow, that is, of less thickness than the thickness of the usual run of boards to be edged and since the said bar 10 is held close up against the lower end of the hangers 8, it follows that one face of the boards to be planed extends beyond the outer face α of the bar 10, such arrangement of parts being provided to permit of using a simple 30 means for holding the board to be edged clamped tightly against the hangers 8 and for such purpose hanger bars 20-20 are pendently held from the inner ends of a pair of horizontal adjusting screw rods 21-21 35 that pass through threaded socket plates 22-22 secured on one of the longitudinal boards 80 in which the crank shafts before referred to are also mounted. The inner ends of rods 21 have a swivel connection 40 with keepers 24 on the upper end of the hanger bars 20 and the lower ends of the said bars have large apertures 25 for loosely riding on stud bolts 26 that are made fast to and are projected inwardly from the 45 bar 9.

50 27-27 designate heads on the rods 21 for turning them, it being understood that by the proper manipulation of the said rods 21, the bars 20 will be moved inwardly against the board to be edged and thereby clamp such board firmly against the hangers 9.

55 28 designates the top or bench board which is of such width and length that when closed down it forms a bench table upon which the board to be edged can be laid flatwise for being planed on its flat side.

60 29 is a transverse board or stop piece secured on one end of the board 28 against which the flat board rests during the operation of planing the flat sides and 30 design-

nates a cross cleat on the underside of the top board which, when the board is closed over the top of the bench engages notches 31 in the side boards 80. The board 28 is hinged to one of the side boards 80, the connection being such that when swung back the said board 28 will hang to the vertical position flatwise over one side of the bench.

65 32 designates the planer which includes side flanges 33-33 for riding upon the upper edges of the planer guide 1.

70 75 From the foregoing description taken in connection with the drawing, the complete arrangement, the manner in which my improved bench is used and the advantages 80 thereof will be readily understood by those skilled in the art to which it relates.

When the top board is swung down my bench can be used as an ordinary work bench and since the operative parts that are 85 used when edging a board are covered, there is little or no danger of the said parts becoming impaired by using the bench for ordinary purposes.

90 What I claim is:

1. In a work bench, the combination of a framing that includes a plurality of oppositely disposed uprights, a horizontal guide rail secured upon the inner side of the upper ends of the said oppositely disposed uprights, means for holding the board to be planed edgewise between the guides and other devices for adjusting the said board holding means for moving the board vertically relatively to the guides and the 100 planer, the said means comprising a longitudinally disposed bar that forms a rest for the board and feed screw connections that connect the bar and the framing for raising and lowering the bar, the said other means 105 including hangers rigidly held at one side of the board supporting bar, other hangers loosely supported on the other side of the said supporting bar and screw rod devices operable from one side of the bench framing 110 for moving the loosely held hangers up against the board to clamp it against the fixedly held hangers.

115 2. In a work bench, the combination of a framing that includes a plurality of oppositely disposed uprights, horizontal guide rails mounted upon the upper ends of the said uprights, means for supporting a board edgewise between the rails to be engaged by the planer, said means consisting of a longitudinal bar of a thickness less than that of the board to be planed having a lateral bracket at each end provided with an internally threaded vertical aperture, upper and lower fixedly held brackets, screw shafts 120 mounted on the upper and lower brackets and engaging the threaded apertures in the brackets in the board supporting bar, means for turning the screw shafts for raising and lowering the said bar, and other means oper- 125 130

able from one side of the bench framing for clamping and holding the board to be planed to its vertically adjusted positions said other means including loosely supported clamping bars for engaging that face of the board that extends beyond the front face of the longitudinal supporting bar and

devices operable from the side of the bench for clamping the loosely held bars against the said board.

THEODORE SWANSON.
